CARRIER WAVE RECEIVER

REISSUED

Application filed December 21, 1931. Serial No. 582,407.

This invention relates to carrier wave receivers and more particularly to receivers including a simple, efficient and inexpensive automatic volume control for rendering 5 the rectified output substantially independent of the strength of the received signals.

An object of the invention is to provide an improved carrier wave receiver in which a single tube performs the function of a 10 demodulator, a rectifier for supplying an automatic volume control voltage and an audio frequency amplifier. A further object is to provide a carrier wave receiver in which a multiple element tube constitutes a diode 15 rectifier which delivers an audio frequency output to a local circuit and a rectified carrier voltage to a gain control circuit, and an audio frequency amplifier.

These and other objects of the invention 20 will be apparent from the following specification when taken with the accompanying drawing in which the single view is a fragmentary circuit diagram of a receiver embodying the invention.

25 In the drawing, the reference numeral 1 identifies a carrier wave amplifier which includes one or more tubes 2 which have input circuits including inductances 3 tuned by condensers 4 which may be, and prefer- 30 ably are, similar sections of a gang con- denser. The low potential terminals of the inductances 3 are grounded on their respective cathodes for carrier frequencies by condensers 5 and are connected to each other 35 and to an automatic gain control voltage line 6 that leads to the novel detector stage that embodies the present invention.

The particular electrical design and the 40 mechanical construction of the carrier wave amplifier do not form a part of the invention. The amplified signal voltage developed across the output terminals 7 of the carrier wave amplifier 1 is impressed upon the tuned input circuit, comprising induct- 45 ance 8 and tuning condenser 9, of the multiple element tube 10. The tube 10 may be, as illustrated, a conventional screen grid tube having a cathode K, a control grid G₁, screen grid G₂ and a plate P, or it may in- 50 clude additional grid elements in accordance

with known tube practice. As will be apparent from the following description, the tube does not function as a conventional screen grid tube but as a tube having a cathode, a control grid and two anodes.

The input circuit 8, 9 is not, however, connected between the cathode K and control grid G₁, but the high potential terminal of the input circuit is connected to the plate P and the lower potential terminal is connected to cathode K through the resistor 11 that is by-passed, for carrier frequencies, by a condenser 12. With this circuit arrangement, rectification of a modulated carrier frequency voltage impressed on the tube from the tuned input circuit 8, 9 takes place by the diode action between anode P and cathode K. The modulation component of the carrier voltage develops thereby an audio frequency component which is impressed on the control grid G₁ for amplification. The average carrier level develops a direct current component of voltage across resistor 11 which is fed back to furnish automatic grid bias for the preceding amplifier stages.

The audio frequency voltage developed across the resistance 11 is impressed upon the control grid G₁, by connecting the grid G₁ to the point 13, i. e., the junction of inductance 8 and resistance 11. 30 This connection includes a condenser 14 to isolate the grid from the direct current component of the rectified carrier voltage, and a filter comprising a resistance 15 shunted to ground by condenser 16, which filter prevents any appreciable carrier frequency voltage from reaching the control grid G₁. A grid bias appropriate for audio frequency amplification is impressed on grid G₁ from a source, indicated as -C, through the bias resistor 17. The primary winding of an audio frequency transformer T is connected between the screen grid G₂ and a source of positive potential +B, and the element G₂ therefore acts as the anode of a triode amplifier having a cathode K and control grid G₁.

The direct current component of the rectified carrier voltage developed across re-

sistor 11 by the diode action of plate P and cathode K is impressed upon the automatic gain control lead 6 by a connection 18 extending from point 13 to lead 6 through the 6 alternating current filter network 19.

The following values are given as indicative of a design suitable for use in the reception of carrier wave signals in the frequency band of from 500 to 1500 kilocycles;

10 Resistance 11 = 200,000 ohms
 Resistance 15 = 100,000 ohms
 Capacity 12 = 500 micromicrofarads
 Capacity 14 = 5,000 micromicrofarads
 15 Capacity 16 = 100 micromicrofarads
 Screen grid voltage, $+B_s$ = 100 volts
 Control grid bias, $-C_s$ = -5 volts

Inductance 8 and tuning condenser 9 were substantially identical with the corresponding tuning elements 3, 4, respectively, of the carrier wave amplifier stages, and the transformer T was designed to give satisfactory audio fidelity characteristics.

As compared with the conventional use of 25 a diode rectifier as a demodulator and a source of gain control voltage, the novel arrangement retains the advantage of the linear characteristics of the diode detector and possesses the further advantage that the 30 rectifier signal is amplified at audio frequency, thus increasing the sensitivity of the receiver. Further advantages arise from the fact that the characteristics of the audio 35 amplifier are not affected by value of the carrier input since the rectified carrier voltage is by-passed from control grid G_1 by the condenser 12. As the primary of the audio transformer T is in the output circuit 40 of an amplifier, and not a detector, the transformer may be of comparatively inexpensive construction as it is not necessary to employ a high impedance primary.

In the usual plate circuit rectifying detectors, the tube impedance across which 45 the audio load is connected has been several times greater than in the case of the same type tube employed as an amplifier. For fidelity over the audio frequency range, the audio load in the plate or output circuit 50 should be constant over the audio range or, if not constant, should have values larger than the internal tube impedance across which it is connected. According to the 55 present invention, the tube impedance across which the audio load is connected is relatively low since the direct current potentials on the control grid and screen grid circuits are appropriate for amplification, 60 not detection. Good fidelity is therefore obtained when the audio frequency transformer has an impedance substantially lower than that of the transformers which, when located in a detector output circuit, 65 would give equally good results.

I claim:

1. The combination with a carrier wave amplifier and a tube having cathode, control grid, screen grid and plate elements, of circuit connections for impressing between the cathode and plate elements the amplified carrier wave voltage developed by said amplifier, said circuit connections including a resistor across which rectified direct current and alternating current voltages are developed by the diode rectifier action of said cathode and plate elements, means for impressing the said alternating current voltage between the control grid and cathode elements, and means for returning to said amplifier a gain control voltage derived from and proportional to the rectified carrier voltage developed across said resistor.

2. The combination with a carrier wave 85 amplifier and a tube having a cathode, first anode, control grid, and second anode; of circuit connections for impressing between the cathode and first anode elements the amplified carrier wave voltage developed 90 by said amplifier, said circuit connections including a resistor across which rectified direct current and alternating current voltages are developed by the diode rectifier action of said cathode and first anode elements, means for impressing the said alternating current voltage between the control grid and cathode elements, and means for returning to said amplifier a gain control 95 voltage derived from and proportional to the rectified carrier voltage developed across said resistor.

3. In a radio receiver, the combination with a carrier wave amplifier; of a tube having a cathode, a rectifier anode, a control grid, and a positively polarized output anode; an input circuit for said tube upon which the carrier wave output of said amplifier is impressed; said input circuit being connected between the cathode and the rectifier anode and including, in series, a carrier-wave coupling circuit, and a resistor shunted by a carrier-wave bypass condenser; means grounding the tube cathode for audio and carrier frequencies, a coupling capacity between control grid and the junction of said resistor and carrier-wave coupling circuit; an audio frequency output circuit connected between the cathode and the positively polarized output electrode; and means impressing between said control grid and cathode a direct current bias potential effective to secure amplification in the audio frequency output circuit of audio frequency variations impressed upon said control grid.

4. In a carrier wave receiver, the combination with a carrier wave amplifier, of a tube having a cathode, control grid, screen grid and plate elements; an input circuit 130

for said tube and upon which the amplified carrier wave output of said amplifier is impressed, said input circuit being connected between the plate and cathode elements of said tube and including, in series, a tuned circuit and a resistor shunted by a carrier wave by-pass condenser, means grounding the tube cathode for audio and carrier frequencies, a capacity between control grid and the junction of said resistor and tuned circuit, an audio frequency output circuit connected between the screen grid and cathode, and means impressing between said control grid and cathode a direct current bias potential effective to secure amplification in the screen grid circuit of audio frequency variations impressed on said control grid.

5 5. The invention as set forth in claim 4, wherein said audio frequency output circuit comprises an inductance and a source of direct current potential, said inductance having an impedance not less than and of the order of the internal tube impedance between 10 screen grid and cathode over the useful audio frequency range, and said direct current potential being effective to secure amplification of the audio frequency variations impressed on said control grid.

15 6. The invention as set forth in claim 4, in combination with means including a direct current circuit connected across said resistor for automatically varying the gain of said amplifier as a function of the rectified carrier voltage developed across said resistor.

In testimony whereof, I affix my signature.
